(57) **CLAIM**

The ornamental design for a touch sensitive device, as shown and described.

DESCRIPTION

FIG. 1 is a perspective view of a first embodiment of a touch sensitive device showing my new design;

FIG. 2 is a front elevational view thereof; and

FIG. 3 is a rear elevational view thereof.

FIG. 4 is an enlarged front elevational view thereof showing the claimed portion, a rear elevational view thereof being a mirror image;

FIG. 5 is a perspective view of a second embodiment of a touch sensitive device showing my new design; and

FIG. 6 is a front elevational view thereof;

FIG. 7 is an enlarged front elevational view thereof showing the claimed portion.

FIG. 8 is a perspective view of a third embodiment of a touch sensitive device showing my new design; and

FIG. 9 is a front elevational view thereof.

FIG. 10 is an enlarged front elevational view thereof showing the claimed portion.

FIG. 11 is a left side elevational view of the embodiments of FIGS. 1, 5 and 8;

FIG. 12 is a right side elevational view thereof;

FIG. 13 is a top plan view thereof; and,

FIG. 14 is a bottom plan view thereof.

Portions shown as broken lines are for illustrative purposes only and form no part of the claimed design. Dot-dash broken lines define the boundaries of, but not included in, the claimed design.
